UNITED STATES PATENT OFFICE.

CHARLES J. PILLIOD, OF TOLEDO, OHIO, ASSIGNOR TO DANIEL SEARLES, TRUSTEE,
OF TOLEDO, OHIO.

ENGINE VALVE.

Application filed September 27, 1920. Serial No. 413,061.

To all whom it may concern:

Be it known that I, CHARLES J. PILLIOD, a citizen of the United States, and a resident of Toledo, in the county of Lucas and State 5 of Ohio, have made an Invention Appertaining to Engine Valves; and I do declare the following to be a full, clear, and exact description of the invention, such as will enable others skilled in the art to which it ap- 10 pertains to make and use the same, reference being had to the accompanying drawings, and to the characters of reference marked thereon, which form a part of this specification.

15 This invention relates to valves for controlling the admission and exhaust of an operating fluid to and from the cylinders of fluid operated engines, other than those of the internal combustion type, and is particu- 20 larly intended for use in connection with steam engines.

The primary object of my invention is to improve on the construction and operation of the valve shown and described in my Patent 25 No. 1,414,152, granted April 25, 1922, whereby to enhance the efficiency and commercial value thereof.

While the invention, in its broader aspect, is capable of embodiments in numerous 30 forms, a preferred and modified embodiment thereof are illustrated in the accompanying drawings, in which,—

Figure 1 is a fragmentary side elevation of a locomotive embodying the invention 35 with the valve and a portion of the associated cylinder in central vertical longitudinal section. Fig. 2 is an enlarged horizontal longitudinal section of the valve. Figs. 3, 4, 5 and 6 are sectional views of the valve with 40 the steam chest ends removed and with the valve parts in different successive positions of a cycle, with the cut-off valve in Figs. 3, 4 and 6 positioned to obtain the maximum point of cut-off and with the cut-off valve 45 in Fig. 5 positioned to obtain a cut-off of the live fluid at approximately one-half of the piston travel. Figs. 7, 8, 9 and 10 are views similar to Figs. 3, 4, 5 and 6, respectively, of a modified form of the valve, and 50 Figs. 11, 12, 13 and 14 are cross sections of the valve taken on the lines 11—11, 12—12, 13—13 and 14—14 in Fig. 2.

Referring to the drawings, 1 designates a steam chest forming a cylindrical valve cas- 55 ing 2, and a side exhaust passage 3 having

communication at each end through passages 4, 4 with the respective end of the valve chamber formed by the casing 2. Live steam which for the purpose of this description may be considered as the operating fluid, is admitted to the valve chamber of the steam chest substantially centrally of its ends through a top conduit 5 communicating with any suitable source of supply, and the valve chamber is provided in its wall at opposite sides of its center with annular recesses 6 and 7, which communicate at their bottoms through ports 8 and 9 with the respective cylinder ports 10 and 11 leading to the opposite ends of the cylinder 12. The exhaust passage 3 of the steam chest has communication through an exhaust port 13 in its bottom side with the main exhaust passage 14 in the cylinder wall. The steam chest at the ends of the valve chamber is closed by heads 15 and 16.

A core member 17 of ring form is fitted in the valve chamber centrally of its ends in covering relation to the live steam supply passage 5 and has one or more openings 17^a in register with said passage to permit the admission of live steam into the valve chamber interiorly of the core. The core 17 has cylindrical flanges 18 projecting in opposite directions from its inner edges, which flanges 85 cooperate with the valve chamber casing at the inner sides of the passages 6 and 7 to form valve guiding spaces therebetween and to protect the valve ends from live steam pressure, as hereinafter described.

90 A pair of telescoped valve sleeves 19 and 20 is provided in each end portion of the valve chamber in closing relation to the respective passages 6 and 7 therein, the inner sleeve 19 being fitted at its inner end portion 95 for longitudinal sliding movements on the adjacent core extension or flange 18 and the outer sleeve 20 being fitted at its inner end portion for longitudinal sliding movements on the sleeve 19 in spaced relation to the wall of the valve chamber. Each inner valve sleeve 19 is shorter than the associated sleeve 20 and has a wall or partition 21 extending across its outer end portion to close communication between the live steam space 22 in the central portion of the valve chamber and the exhaust spaces at the outer end portions 100 of the valve chamber. The partitions 21 of the two valve sleeves 19 are rigidly connected by a spacing member 23 and bolt 24 to 110

cause the two sleeves to have movements in unison and to cooperate to form a plug valve.

A cut-off sleeve 25 is mounted on each valve sleeve 20 and has a close sliding fit between such sleeve and the valve casing 2. Each cut-off sleeve is adapted to close the respective casing recess 6, 7 to the interior of the valve chamber except for the provision of two longitudinally spaced sets of inlet ports 26 and exhaust ports 27 provided in annular series in each cut-off sleeve.

Each set of valve sleeves 19 and 20 has a set of radial inlet ports 28 and 29 provided respectively therein in annular series and adapted to register with each other and to open communication between the ports 26 of the associated cut-off sleeve 25 and the live steam space 22 to admit live fluid to the respective end of the cylinder 12 during a predetermined portion of the relative movements of said sleeves, as will be hereinafter more fully described. Each valve sleeve 20 has an annular series of radial exhaust ports 30 disposed at the outer side of the set of ports 29 therein and adapted to be uncovered by the sleeves 19 and 25 and to register with the exhaust ports 27 in the respective cut-off sleeve 25 during the period of exhaust from the adjacent cylinder end. It is evident that the periods of fluid admission to and exhaust from a cylinder may both be varied to suit running conditions by movements of the cut-off sleeves 25.

The inner sleeves 19, 19 are connected by a rod 31 to the radius rod 32 of the valve gear, and the sleeves 20, 20 are rigidly connected to each other and to the combination lever 34 of the valve gear by a rod 33, so that the inner set of sleeves 19 is operated by the reversing means of the valve gear and the outer set of sleeves 20 is operated by the piston rod cross-head of such gear. It is thus evident that the valve sleeves 19 and 20 have their differential movements controlled by the movements of the radius rod 32 and combination lever 34 of the valve gear. The cut-off sleeves 25, 25 have rods 35 projecting from their outer ends through the ends of the valve chest and connected to respective levers 36, 36, which are in turn connected to any suitable control by reach rods 37. The control rods for the several sleeves project through stuffing boxes in the respective ends of the valve chest.

It will be understood that while I have particularly shown my valve in connection with one type of valve gear, it is not restricted to use in connection therewith, but may be coupled up to any valve gear of either the radial or eccentric driven type, and may also be used in connection with stationary and marine engines to control the admission of steam to, and its exhaust from, the engine cylinder.

It is evident that the design of my valve is such that it can be inserted into the valve casings of engines now in use and substituted for the steam control valves of the plain plug or piston type used therein without changing the location of the ports and the steam distributing channels or recesses in such casings.

In describing the operation of my valve mechanism, reference is made particularly to Figs. 3 to 6, in each of which the points on the circles at the left indicate the relative valve gear positions for the different valve sleeves, as in all types of gears or operating means for the valve sleeves the position of the eccentric or reversing means is 90° in advance of the cross-head movement. For this reason such movements are illustrated diagrammatically at the left of each of said figures and designate the different eccentric and cross-head positions for different positions of the valve sleeves. In other words, when the cross-head is at the extreme of its movement in either direction the eccentric is at the center of its travel, and vice versa. In the valve gear illustrated the radius rod 32 on one side of the locomotive is operated from the cross-head on the opposite side, this being necessary in the present case as all valve motions are derived from the cross-heads.

In Fig. 1 the cross-head 38 of the valve gear is at the extreme of its left stroke, with the upper end of the combination lever 34, which connects the valves 20, at the extreme of its right stroke, as illustrated in Fig. 3, while the radius rod 32, connecting the valves 19, is at mid-position due to the mid-position of the cross-head on the far side of the locomotive. In Figs. 1, 2 and 3 the valves are in what is known as "lead position" with respect to the left end of the cylinder 12 where admission is beginning. When the valve sleeves are in this position steam is beginning to enter the left end of the cylinder through the valve ports 28, 29, 26 and valve chest and cylinder ports 6, 8 and 10. During the continued movement of the valve sleeves, which is toward the left and at different speeds, the ports 28 and 29 continue to open and then to close until the full cut-off position shown in Fig. 4 is reached. All valve ports on left end then remain closed until the "release position" shown in Fig. 6 is reached when the left end exhaust ports 30 begin to open, such opening continuing until the valves have nearly reached the position shown in Fig. 3. The exhaust then takes place from the left end of the cylinder through ports 10, 8 and 6 in the cylinder and valve chest and through ports 27 and 30 in the left end valve sleeves 25 and 20 into the interior outer end portions of said valves and outward therefrom through the valve chest.

end exhaust port 4 into the expansion passage 3 in the chest from which it passes through the chest port 13 and main exhaust passage 14. It will be understood that the 5 opening and closing of the ports at the opposite end of the valve is exactly the same with respect to the right end of the cylinder, as described for the left. In Fig. 5 the cut-off sleeves have been advanced or 10 moved inward to effect a cut-off at substantially half of the stroke. Other positions of the cut-off sleeves may be obtained so that the steam cut-off may be varied at will and without effecting the movements of the 15 valves 19 and 20 which are constant at all times.

When it is desired to reverse the movement of the engine the reverse mechanism is operated to effect a shifting of the valve 20 19 so that instead of the eccentric position being as shown in Fig. 3 it will be 180° in advance of such position.

It is evident that to cut off the steam the cut-off sleeves 25, 25 are moved in opposite directions by movements of the control mechanism and that the steam may have a hundred per cent cut-off, if desired, although it is usually not practical to exceed a ninety per cent cut-off. The control 30 of the port openings and cut-off sleeves is entirely independent of the exhaust, thereby not sacrificing release to obtain any desired range of steam admission.

It is evident with the use of my valve 35 that the opening and closing movements of the valves 19 and 20 remain constant, while the steam cut-off portions of the cut-off valves may be varied at will, thus enabling a maximum efficiency for either the normal 40 running or starting positions, to be obtained; that the constant events, such as the exhaust release, exhaust closure, steam admission and steam pre-admission, are determined by the design or service requirements, and that the valve sleeves are protected at their inner ends from live steam 45 pressure by the valve chest and core arrangement. It is also evident that with my valve there is no limitation as to events to be secured, that is, any release, any closure, or any cut-off can be obtained.

The primary differences between my present valve and that of my said prior application reside in shortening the core 50 member so that it extends only to the admission ports, changing the construction of the inner valve sleeves to perform a part of the function previously performed by the core member, and extending the outer ends of 55 the cut-off sleeves beyond the ends of the ports in communication with the cylinder so that the ends of the cut-off sleeves will not be subjected at any time to live steam pressure.

60 In Figs. 7 to 10 the core member is shown

as omitted and end bushing members 40, 40 substituted therefor. These bushings are fitted in the end portions of the valve chamber, with their inner ends in spaced relation and in communication with the central live fluid 70 space of the chamber, and form bearings for the respective cut-off sleeves and for the inner end portions of the outer valve sleeves. The bushings are provided with ports 41 opening into the valve chest recesses 6^a and 7^a in communication with the cylinder ports. In this form of the invention 42 designates the plug valve in which the inward sleeve-like extensions of the valve 19 shown in the other figures are 80 omitted; 43 are the outer sleeve valves and 44 the cut-off sleeves.

I wish it understood that my invention is not limited to any specific construction, arrangement or form of the parts or location of the ports, as it is capable of numerous modifications and changes without departing from the spirit of the claims.

Having thus described my invention, what I claim as new, and desire to secure by Letters Patent, is,—

1. In a fluid pressure engine, means forming a valve chest having a centrally disposed live fluid admission passage, a port at each side of the central passage forming a cylinder admission and exhaust port, and a main exhaust passage in communication with the chest ends, a pair of rigidly connected sleeve valves mounted in the chest in axially spaced relation at opposite sides of its live admission passage, a second pair of rigidly connected sleeve valves mounted in the first pair and having their outer ends closed, with the space between the same in permanent communication with the supply passage, said valves having ports which cooperate upon a relative movement of the inner and outer valves to control the admission and exhaust of fluid to and from an associated engine cylinder through the respective cylinder port, the inlet of steam to the cylinder being from the space between the ends of the inner valve sleeves and the exhaust being into the respective outer end portions of the chest and thence to the main 105 exhaust passage, and means for imparting predetermined travel to each pair of valves, said valve chest means having portions which enter and serve to seal the inner end edges of the first pair of sleeve valves.

2. In a fluid pressure engine, means forming a valve chest having a live fluid admission passage and cylinder admission and exhaust ports at each side thereof and a main exhaust passage in communication with its 115 ends and also having an annular outwardly facing recess between the admission passage and each cylinder admission and exhaust port, a pair of rigidly connected sleeve valves mounted in the chest and having 120

- 4 their outer ends closed and their inner ends fitted into the respective chest recesses, a second pair of rigidly connected sleeve valves mounted in the chest in axially spaced relation at opposite sides of its live fluid admission passage and around the first sleeve valves, said sleeve valves having ports which cooperate upon a relative movement of the inner and outer valves to control the admission and exhaust of fluid to and from an associated engine cylinder through the respective cylinder port, the inlet of steam to the cylinder being from the space between the closed ends of the inner sleeve valves and the exhaust being into the respective outer end portions of the chest and thence to the main exhaust passage, and means for imparting predetermined travel to each pair of valves.
- 5 10 15 20 25 30 35 40 45 50 55 60 65 70 75 80 85 90 95 100 105 110 115 120 125 130
3. In a fluid pressure engine, means forming a valve chest having a live fluid inlet, an exhaust passage and cylinder admission and exhaust ports, valve means of sleeve form mounted in the chest and having admission and exhaust ports in association with each cylinder port, a piston valve mounted in the valve means and having spaced ends with the space therebetween in permanent communication with the live fluid inlet and having ports associated with the cylinder ports, and means for operating the valve means and piston valve to cause a periodical register of the piston valve ports and valve means inlet ports to admit live fluid to the respective cylinder ends and a periodical opening of the valve means exhaust ports to the respective cylinder ports and exhaust passage, and means independent of said valve means and said piston valve operable to vary the closure of the admission ports.
4. In a fluid pressure engine, means forming a valve chest having a live fluid inlet intermediate its ends, a main exhaust passage in communication with its ends, and cylinder admission and exhaust ports at opposite sides of the fluid inlet, a double sleeve valve mounted in the chest and having inlet and exhaust ports at each end for register with the respective cylinder ports, a hollow piston valve mounted in the sleeve valve in permanent communication between its ends with the live fluid inlet and having ports at its end portions associated with the cylinder ports, and means for imparting predetermined movement to the sleeve and piston valves to cause a periodical registering of the piston valve ports with the respective inlet ports of the sleeve valve to admit live fluid to the respective cylinder ends and a periodical opening of the sleeve valve exhaust ports to the respective cylinder ports and exhaust passage, and means normally standing at rest but operable to vary the closure of the admission of fluid to
- the cylinder, said last means operating independent of the double sleeve valve and of the piston valve.
5. In a fluid pressure engine, means forming a valve chest, means forming fluid pressure supply and exhaust passages, a set of constant travel valves working one within another for controlling the admission and exhaust to and from an associated engine cylinder, the inner valve being of hollow piston form, a variable travel cut-off valve cooperating with one of the constant travel valves to cut off the fluid supply to the cylinder at any predetermined point of travel of the cooperating valve, and means for imparting predetermined differential movements to the constant travel valves.
6. In a fluid pressure engine, means forming fluid pressure supply and exhaust passages and cylinder ports, a pair of rigidly connected sleeve valves, a second pair of rigidly connected sleeve valves mounted in the first pair and having their outer ends closed with the space between the same in permanent communication with the supply passage, said valves cooperating to control the admission and exhaust of fluid to and from an associated engine cylinder, means for imparting constant predetermined relative travel to the inner and outer sleeve valves, and cut-off sleeves mounted on the outer set of valve sleeves and extending at their outer ends beyond the respective cylinder ports.
7. In a fluid pressure engine, means forming fluid pressure supply and exhaust passages and cylinder ports, a pair of rigidly connected sleeve valves, a second pair of rigidly connected sleeve valves mounted in the first pair and having their outer ends closed with the space between the same in permanent communication with the supply passage, said valves cooperating to control the admission and exhaust of fluid to and from an associated engine cylinder, means for imparting constant predetermined relative travel to the inner and outer sleeve valves, and cut-off sleeves mounted on the outer set of valve sleeves and extending at their outer ends beyond the respective cylinder ports, said first means having provision for enclosing the inner ends of the different valve sleeves to protect them from live fluid pressure.
8. In a fluid pressure engine, means forming a cylindrical steam chest having a fluid supply passage at its center and exhaust passages at its ends and cylinder ports between each exhaust passage and supply passage, a core member fitted in the central portion of the chest with a transverse opening therethrough in communication with the supply passage and with cylindrical flanges extending outward from the inner edges of its opposite ends to cooperate with the chest

wall to form annular recesses, three sets of telescoped sleeves mounted in the chest and having their inner ends projected into the respective recesses formed by the core member and chest to protect them from live fluid pressure, the outer set having openings in register with the cylinder ports and extending at their outer ends beyond said ports, the outer set forming cut-off sleeves and extending at their outer ends beyond the cylinder ports and having openings in register with such ports, the intermediate set of sleeves each having inlet and exhaust ports for register with the respective cylinder ports, and the inner set of sleeves each having ports for registering with the respective inlet ports of the intermediate sleeves and having their ends closed without said ports, means for imparting predetermined constant differential movements to the inner and intermediate sleeve sets to periodically open and close the live fluid space between the ends of the inner set to the cylinder ports and to periodically open the cylinder ports to the exhaust passages of the chest through the exhaust ports of the intermediate sleeve, and means for imparting opposed uniform movements to the cut-off sleeves.

9. In a fluid pressure engine, means forming a valve chest having a centrally disposed live fluid admission passage, a port at each side of the central passage forming a cylinder and admission and exhaust port, and a main exhaust passage in communication with the chest ends, a pair of rigidly connected sleeve valves mounted in the chest in axially spaced relation at opposite sides of its live admission passage, a second pair of rigidly connected sleeve valves mounted in the first pair and having their outer ends closed, with the space between the same in permanent communication with the supply passage, said valves having ports which cooperate upon a relative movement of the inner and outer valves to control the admission and exhaust of fluid to and from an associated engine cylinder through the respective cylinder port, the inlet of steam to the cylinder being from the space between the ends of the inner valve sleeves and the exhaust being into the respective outer end portions of the chest and thence to the main exhaust passage, means for imparting predetermined travel to each pair of valves, said valve chest means having portions which enter and serve to seal the inner edges of the first pair of sleeve valves, and means to vary the fluid admission to the cylinder independent of the said two pair of sleeve valves.

In testimony whereof I have hereunto signed my name to this specification.

CHARLES J. PILLIOD.
